(57) **CLAIM**

The ornamental design for a multi-socket wrench, as shown and described.

DESCRIPTION

FIG. 1 is a front perspective view of a multi-socket wrench according to the present invention;

FIG. 2 is a left side view of the multi-socket wrench of FIG. 1;

FIG. 3 is a right side view of the multi-socket wrench of FIG. 1;

FIG. 4 is a front view of the multi-socket wrench of FIG. 1;

FIG. 5 is a back view of the multi-socket wrench of FIG. 1;

FIG. 6 is a top view of the multi-socket wrench of FIG. 1; and,

FIG. 7 is a bottom view of the multi-socket wrench of FIG. 1. The broken lines showing elements on the multi-socket wrench is included for the purpose of illustration and forms no part of the claimed design.
